UNITED STATES PATENT OFFICE.

THOMAS H. BURRIDGE, OF ST. LOUIS, MISSOURI.

STREET-CAR MOTOR.

SPECIFICATION forming part of Letters Patent No. 393,207, dated November 20, 1888.

Application filed March 29, 1888. Serial No. 268,760. (No model.)

To all whom it may concern:

Be it known that I, THOMAS H. BURRIDGE, of the city of St. Louis, in the State of Missouri, have invented a certain new and useful 5 Improvement in Street-Car Motors, of which the following is a full, clear, and exact description, reference being had to the accompanying drawings, forming part of this specification.

This is a device for driving the car with compressed air carried in a reservoir upon the car. The air may be used either in a reciprocating engine, as shown, or in a rotary engine, no novelty being claimed in the engine *per se*. The air in the reservoir is expanded by heat from gas-flames fed by gas from a reservoir in which it is carried on the car in a compressed condition, or by a carbureting device upon the car, as shown. The heated products of combustion are carried from a pipe passing 15 through the air-reservoir to a chamber surrounding the cylinder of the engine and forming a warming-jacket.

Figure I is a top view of the apparatus. Fig. II is a longitudinal section at II II, Fig. 25 III. Fig. III is a horizontal section at III III, Fig. II.

At 1 are the drive-wheels, and at 2 other supporting-wheels, of which 3 is the axle. The axle of the drive-wheels may be made in two 30 parts, 4, each of which has at its inner end a crank, 5. The two cranks are connected in such relative position that each will carry the other over the dead-center. The axle 4 may be cast in one piece, with the two cranks 5 upon it. To each crank 5 is connected a rod, 6. One of the connecting-rods 6 is strapped 35 to a bracket, 7, upon the piston-rod 8. This piston-rod is tubular and within it works another piston-rod, 9. To each of these rods is attached a piston which works in a separate 40 chamber to the other piston, the cylinder being divided into two chambers by a transverse partition or diaphragm, through which the solid piston-rod 9 passes.

45 As heretofore said, no novelty is claimed in the engine *per se*, as it is not new in the form shown, and any suitable engine may be used to turn the axle or axles of the drive-wheels. The engine which is shown is described in the 50 patent of D. P. Kane, No. 306,930, dated October 21, 1884. At 10 are shown the reservoirs or chambers containing the compressed

air. These may be filled with air under pressure at the end of the car-line or at any point on the line. 11 is a pipe leading from the vessels 10 to the valve-chest 12 of the engine. 13 are eccentrics on the axle, working by the eccentric-rods 14 the rock-shaft 15.

16 are arms on the rock-shaft, to which the eccentric-rods are strapped, and 17 are arms 60 on the rock-shaft, to which the stems 18 of the slide-valves are strapped. The device, as above described, will suffice to drive the car as long as the air in the reservoirs 10 is under sufficient pressure; but when the pressure is 65 reduced below this point it must be increased by some means to render the motor effective.

I shall now describe the apparatus for the increase of pressure of the air in the reservoirs 10.

70 19 is a rotary fan turned by a belt, 20, that passes around a pulley, 21, on the drive-axle 4, and a pulley, 22, on the shaft of the blower. The blower discharges air through the nozzle 23 into one side of a box or case, 24, within 75 which turns a wheel, 25, having on it radial buckets or wings 26, whose ends are in close proximity to the ends of the box, and whose upper edges, when they are in a vertical position, are in close proximity to the top of the 80 box. The buckets are formed of wire-gauze stretched on a frame. The bucket-shaft is horizontal and turns freely in bearings 27 in the side of the closed box 24. The box 24 is partly filled with water, as seen at 28 in Fig. 85 II, so that as the wheel turns the buckets are immersed in water and carry up the liquid with them as the wheel is turned by the pressure of the air upon the elevated buckets. The wet buckets arrest all the dust which may be 90 mixed with the air, so that the air leaving the box is clear. The box 24 contains, preferably, more than one of these wheels 25, two being shown in Fig. II, (one in full lines and the other in broken lines.)

95 The clear air leaves the box 24 through a pipe, 29, that descends to the lower part of a closed box or tank, 30, containing benzole or other hydrocarbonaceous liquid, as seen at 31, Fig. II. The air is forced by the blower 100 through the pipe 29 and ascends through the benzole or other liquid, 31, where the inflammable gas mixes with the air from the upper part of the box 30. The air, laden with the

gas, passes into a pipe, 32, which extends beneath a box or case, 33, having, preferably, a number of partitions, 34, extending from the bottom to near the top, so as to separate the case into a number of compartments, 35, which contain sponge or other porous material saturated with petroleum, spirits of turpentine, or other hydrocarbonaceous liquid. The pipe 32 has a branch, 36, leading into the lower part of each of the compartments 35, and having a fixed hood, 37, to prevent the absorbent material entering the tops of the branch pipes 36. Between the hoods and the pipes is space for the exit of air from the branch pipes into the compartments 35. The air will become additionally carbureted in passing through the compartments 35, and will become freely inflammable.

38 is a pipe extending from the case 33, and having branches 39 leading to gas-burners 40 in combustion-chambers 41, that are within the reservoirs 10. Only sufficient air is allowed to enter the chambers 41 to supply oxygen for the combustion of the gas.

42 is a door in each chamber that may be opened to get access to the same.

The products of combustion escape from each chamber 41 through a coiled pipe, 43, which extends through the reservoir 10, so as to radiate heat throughout the reservoir or chamber and to heat the air in the chamber or vessel. The pipes communicate with a jacket-chamber, 44, surrounding the engine-cylinder, so as to prevent the cooling of the cylinder and consequent reduction in the pressure of the air in the cylinder.

The invention in its most simple form may have a quantity of compressed city gas or other inflammable gas in a reservoir in communication with the burners 40 with a valve or cock, by which the gas may be turned onto burners when desired. The case 33 may represent such a reservoir.

When the term "compressed air" is used throughout the specification, it is meant to indicate air above the normal atmospheric pressure, whether such pressure is produced by mechanical means or by expansion of the air by heating it above the normal temperature.

50 I do not claim, broadly, a car-motor driven by compressed air; but

I claim herein as new and of my invention—
1. The combination of a car, a reservoir for

compressed air, an engine adapted to drive the car, and with valve-chest in communication with said reservoir, a closed chamber, gas-burners within said chamber, and a pipe having one end opening into and extending from said chamber through the air-reservoir, substantially as and for the purpose set forth. 55

2. The combination, in a car, of a reservoir for compressed air, an engine in communication with the reservoir, gas-burners adapted to heat the reservoir, a chamber containing the burners, a pipe open at one end to said chamber, and extending through the air-reservoir and discharging into a warming-jacket surrounding the engine-cylinder, and an eduction-opening at the lower part of said jacket. 60

3. The combination, in a car, of the reservoir for compressed air, an engine in communication with the reservoir, gas-burners adapted to heat the reservoir, a closed chamber arranged in the bottom of said reservoir and containing the burners, a coiled pipe open at 75 one end to said chamber and extending through the air-reservoir and discharging into a warming-jacket surrounding the engine-cylinder, and an eduction-opening at the lower part of said jacket, substantially as set forth. 70

4. The combination, with a car, of a reservoir for compressed air, an engine adapted to drive the car and driven by compressed air from the reservoir, a warming-jacket surrounding the cylinder of said engine, a carburetor through which the air is forced by a blower driven by the engine, gas-burners fed by the carburetor contained in a chamber of the compressed-air reservoir, and a pipe extending from the burner-chamber through the compressed-air reservoir to said jacket, substantially as and for the purpose set forth. 85

5. The combination, with a car, a reservoir for compressed air, and the engine connected with said reservoir and adapted to drive the car, of gas-burners for heating said reservoir, a carburetor supplying gas to said burners, a blower connected with said carburetor, a closed chamber containing liquid interposed between said blower and carburetor, and the wheels 25, 90 having perforate wings 26, in said chamber, substantially as set forth. 95
